UNITED STATES PATENT OFFICE.

MAURO GONZALEZ SÁENZ, OF COLÓNIA POSTAL, GENERAL ANAYA, MEXICO.

ELECTRICAL CONNECTER SOCKET OF THE WALL AND PLUG TYPE.

Application filed August 6, 1925, Serial No. 48,549, and in Mexico June 8, 1925.

This invention relates to new and useful improvements in electric connector sockets of the wall and plug type.

The primary object of the invention is to provide an electric socket which is suitable for use with male connector or plug-in members having either cylindrical or blade terminals.

A further object of the invention is to provide a socket having a pair of female terminals suitable for receiving cylindrical male terminals and, also, a pair of female terminals suitable for receiving blade male terminals with the respective terminals of each pair connected in parallel with the other pair.

Other objects and advantages of the invention will be apparent during the course of the following description.

20 In the accompanying drawing forming a part of this specification and in which like numerals are employed to designate like parts throughout the same,

Figure 1 is a front elevational view of a wall socket embodying this invention,

Figure 2 is a sectional view taken upon line II—II of Fig. 1,

Figure 3 is a rear elevational view of the type of socket shown in Figs. 1 and 2,

30 Figure 4 is a detail perspective view of a pair of terminal members employed in the socket structure shown in Figs. 1 to 3 inclusive,

Figure 5 is an elevational view of a plug socket embodying this invention,

Figure 6 is an elevational view of the inner end of the plug socket shown in Fig. 5;

Figure 7 is an elevational view of the outer end of the structure shown in Figs. 5 and 6,

Figure 8 is a perspective view of the body portion or insulator for the type of socket shown in Figs. 5 to 7 inclusive,

45 Figure 9 is a longitudinal sectional view of the structure shown in Figs. 5 to 7 inclusive,

Figure 10 is a similar view to Fig. 9, but taken at right angles thereto,

50 Figure 11 is a perspective view of the two female terminals which form a part of the socket structure shown in Figs. 5 to 10 inclusive and adapted for receiving male terminals of cylindrical formation, and

55 Figure 12 is a similar view to Fig. 11, but

shows the female terminals employed for receiving male terminals of the blade type.

In referring to the accompanying drawing, reference will first be made to the type of socket shown in Figs. 1 to 4 inclusive 60 wherein the numeral 5 designates the body portion or insulator of a wall socket which is of substantially cylindrical formation. The front face of the body portion or insulator 5 is designated by the reference numeral 6 and is surrounded by the annular bead or flange 7. In Figs. 2 and 3 the rear face 8 of the member 5 is illustrated as having formed therein the arcuate grooves 9 having the lateral extensions 10 formed at 70 the opposite ends thereof and extending to the periphery of the body portion. These extensions 10 and arcuate grooves 9 are provided for accommodating circuit wires and will permit the body portion or insulator 5 75 to be mounted upon a wall or other surface with the rear face 8 flushly engaging the same by any suitable fastening means which may be inserted through the apertures 11.

Arranged in a circular series around the 80 axis of the body portion or insulator 5 are the diametrically opposed openings 12 which are of rectangular formation in cross-section and the diametrically opposed openings 13 which are of circular or cylindrical formation in cross-section and are arranged at 85 right angles to the openings 12. The front face 6 of the body portion or insulator 5 is countersunk at the two points designated by the reference numerals 14, which countersunk portions are concentric with the cylindrical openings 13. The rear face 8 of the body portion or insulator 5 is cut away at the two places 15 in a manner to connect or form communication between the arcuate 95 grooves 9 and the inner ends of the openings 12 and 13.

In Fig. 4 there is shown in detail a pair of electrically connected, female terminals and it will be seen by inspecting Fig. 3 that 100 two of these structures are employed in the wall socket shown in Figs. 1 to 3 inclusive. It is believed that a detailed description of the structure shown in Fig. 4 will be sufficient for these terminal members. The reference numeral 16 designates a plate-like metallic portion which is formed at one end with a lateral projection 17 having connected to the outer end thereof the lateral projection 18 carried by an inverted U-shaped strip 105 110

19 or a strip bent upon itself at 20. The plate-like portion 16 is suitably apertured for permitting the tubular member 21 to be connected thereto. A further aperture is formed in the outer end portion of this plate 16 and is intended to receive the wire connecting screw 22 which is employed for establishing a connection between a line wire and the terminal members 19 and 21. By inspecting Fig. 2, it will be seen that the opposite ends of the tubular connector 21 are flanged or bent outwardly for fastening the entire structure shown in Fig. 4 to the body portion or insulator 5, the said tubular terminal member 21 being received within an opening 13 in the member 5. The body portion or insulator 5 is further provided with a socket 23 for loosely receiving the inner end of the connector screw 22. By inspecting Figs. 1 and 3, it will be seen that the plate member 16 and lateral projection 17 are received within the cutaway portion 15 formed in the rear face 8 of the member 5 and when arranged in this cutaway portion, the inverted U-shaped contact or terminal 19 will project through an opening 12 for presenting the bent end 20 of the same to the front face 6 of the body portion 5.

It will now be seen that a plug-in member carrying two male cylindrical terminals may be connected to the conductor plates 16 by having the terminals inserted into the bores of the tubular terminals 21 and, also, that a plug-in member having a pair of male blade terminals may be connected to the plates 16 by inserting the terminals into the openings 12 of the element 5, the strips 19 being of a suitable resilient nature to yield or permit being compressed to allow the entrance of these male blade terminals.

The plug socket illustrated in detail in Figs. 5 to 12 inclusive includes a substantially cylindrically-shaped body portion or insulator 24 which has the reduced inner end portion 24^a. Arranged in substantially circular series and extending longitudinally thru the body portion 24 are the diametrically opposed openings 25 which are of rectangular formation in cross-section and the diametrically opposed openings 26 which are of circular formation in cross-section and are arranged at right angles to the openings 25. The reduced end portion 24^a of the insulator 24 is provided with longitudinally extending grooves or recesses 27 which are extensions of the openings 25 and the longitudinally extending grooves or recesses 28 which are extensions of the circular openings 26. The free end 29 of the reduced end portion 24^a is of substantially conical formation with the flattened end 29^a. The reduced end portion 24^a is grooved at 30, as best illustrated in Figs. 8 to 10 inclusive.

In these same figures, and also in Fig. 6, the conical portion 29 is illustrated as having

formed thereon the axially extending tits 31.

Surrounding the reduced portion 24^a is a thin metallic ring 32 which is formed with a spiral thread and has its inner edge 33 bent inwardly to be received within the groove 30 for fastening the ring upon the reduced end portion. In Fig. 6 the outer edge of the ring 32 is illustrated as being bent inwardly at 34 and as having diametrically opposed notches 35 formed therein for receiving the tits 31 formed on the conical end 29 of the insulator 24. The reception of these tits 31 in the notches 35 will prevent the ring 32 from rotating about the reduced end 24^a.

In Fig. 11 there are shown two female, 80

cylindrical terminals 36 and 37. The terminal 36 is formed with a tongue 38 which is apertured for the reception of a rivet 39, see Fig. 9. This cylindrical terminal 36 is intended to be inserted in one of the openings 26 and to be connected to the threaded ring 32 by the rivet 39. The remaining end of this member 36 is flanged at 40, as best illustrated in Figs. 9 and 11. It will be seen that this member 36 also functions to prevent the ring 32 from being removed from the reduced end 24^a and, further, from rotating about this end portion. The cylindrical terminal 37 is formed with a ribbon-like extension 41 which is bent at an obtuse angle to form the portion 42 having at its free end the laterally extending apertured ear 43. This member 37 is intended to be received within the remaining opening 26 and the ribbon like extension 42 is received within the adjacent groove 28 so that it will not contact with the ring 32. The apertured ear 43 flushly engages the flattened end 29^a of the conical end portion 29 and is secured thereto by the rivet 44, best shown in Figs. 9 and 10.

In Fig. 11 there is shown a terminal formed from a suitable strip of metal and having the U-shaped contact portion 45, the stem 46, and the bent over ear portion 47

which is apertured for receiving the rivet 48 employed for fastening this apertured ear 47 to the ring 32. Figure 10 shows this member 45 received within one of the openings 25 formed in the body portion or insulator 24. Figure 12 further illustrates a terminal formed from a strip of metal and including the U-shaped contact portion 49, the stem 50, and the apertured ear 51. Fig. 10 also shows this terminal member received within the remaining opening 25 with the apertured ear held in flush engagement with the flattened end 29^a of the insulator 24 by the previously referred to rivet 44.

It will now be seen that the terminal members 36 and 45 are connected in parallel to the ring 32 while the terminal members 37 and 49 are electrically connected together by the rivet 44.

It will now be seen that this plug socket 130

may be employed for having connected thereto a plug-in member provided with a pair of cylindrical, male terminals or a pair of blades, male terminals in the same manner as described in connection with the wall socket shown in Figs. 1 to 4 inclusive.

It is to be understood that the forms of this invention herewith shown and described are to be taken as preferred examples of the same, and that various changes in the shape, size, and arrangement of parts may be resorted to without departing from the spirit of the invention or the scope of the subjoined claims.

Having thus described the invention, I claim:—

1. An attachment plug receptacle comprising an insulating body with recesses in one end thereof, two pairs of passages extending between the recesses and the front of the body, one passage of each pair being enlarged at the front of the body, in combination with two pairs of contacts having members disposed in the respective recesses and each disposed in its respective one of the pairs of passages, one contact of each pair being adapted to co-operate with one form of plug jack, the other contact of each pair being tubular to cooperate with a different form of plug jack and having one end flanged outwardly at the bottom of the enlarged front end portion of the passage in which it is disposed, the differing contacts

of each pair being electrically connected together and adapted for connection with separate conductors at said recessed end of the body.

2. An attachment plug receptacle comprising an insulating body with recesses in the back thereof, a pair of passages extending between each recess and the front of the body, one passage of each pair being enlarged at the front of the body, and a groove in the back of the body between each recess and a side of the body, in combination with a pair of contact devices having plate members seated in the respective recesses and each having a pair of contacts disposed in its respective pair of passages, one contact of each pair being integral with its plate member and adapted to cooperate with one form of plug jack, the other contact of each pair being tubular to cooperate with a different form of plug jack and being attached at one end to its plate member and having its other end flanged outwardly at the bottom of the enlarged front end portion of the passage in which it is disposed, said plate members having portions extending from the respective recesses into the respective back grooves of said body and equipped with means for connecting conducting wires thereto.

In testimony whereof I affix my signature.

MAURO GONZALEZ SÁENZ.
